UNITED STATES PATENT OFFICE.

ALBERT D. TRENO, OF GLOUCESTER, MASSACHUSETTS, ASSIGNOR TO JOHN HAYS HAMMOND, JR., OF GLOUCESTER, MASSACHUSETTS.

SYNCHRONIZING MECHANISM.

Application filed August 22, 1922. Serial No. 583,597.

This invention relates to improvements in synchronizing mechanisms, and more particularly to mechanisms adapted for synchronizing multiple player actions used in 5 automatic musical instruments.

Some of the objects of the present invention are to provide improved means for moving a plurality of strips in synchronism; to provide for moving the strips at substantially the same linear velocity; to provide 10 means to modify the motion of some of the strips to correct their alignment should they, for any reason get out of step with the remaining strips; to retard the movement periodically of such actions as may be in advance of other actions; and to permit the starting of all actions synchronously when the last action has caught up with the others.

Other objects will appear from the following description taken in connection with the accompanying drawing, in which there is shown diagrammatically so much of an automatic player as is necessary to an understanding of the invention.

Referring to the embodiment of the invention shown, there is provided a plurality of player actions 10, 11, 12, 13 and 14, driven by a common source of motive power such as a motor 15. Interposed between each of 20 the actions and the motor is a clutch, such as a friction clutch 16 for mechanically engaging and disengaging the drive motor and the respective action.

For controlling the clutch 16 associated with the actions 10, 11, 12, 13 and 14 there is provided a corresponding plurality of control devices 21, 22, 23, 24 and 25 which are operated by the player actions. As the construction of the various actions, clutching 30 means and control devices, are identical, a description of one set will serve for all.

The player action comprises two substantially parallel rolls 30 and 31 spaced apart and mounted on shafts 32 and 33 respectively. The shafts 32 and 33 are journaled in a supporting framework 34, and thus the rolls 30 and 31 may rotate freely. A perforated strip 35, of paper or like material, is wound upon the rolls 30 and 31 in such manner that in passing from one roll to the other it passes directly over a fixed tracker bar 36. The tracker bar 36 is supported in the framework 34 in any suitable manner. The tracker bar 36 is provided in the face adjacent to the paper strip 35, with outlet holes

including a control hole 37 and a plurality of note holes such as 38, one for each note to be played. Thus the perforations in the strip register with these holes to control the instrument. The perforations in the strip 60 consist of a series of equally spaced control holes 39 which register in sequence with the control hole 37, and a plurality of series of note holes 40, whose arrangement is in accordance with the music to be played, and 65 which register with the respective note holes 38 of the tracker bar.

For retarding the movement of the roll 30 and thus maintaining the paper strip taut while unwinding therefrom, there is provided a spring 41 having one end affixed to the framework 34, and the other end pressed against a suitable disk affixed to a protruding end of the shaft 32. The other shaft 33 extends outwardly of the framework 34 and 70 through a suitable bearing in an auxiliary framework 45 and into a bearing in a supporting post 46. Intermediate the post 46 and the framework 45 there is pinned to the shaft 33 a collar 47 against which presses a 75 coiled spring 48.

The clutching means comprises a beveled friction disc 50 having an integral hub with a groove 51 therein. The disc 50 and its hub 80 is slidably mounted on the shaft 33, there being provided a suitable keyway and tongue 85 to prevent relative rotary motion of these parts. A bracket 52 affixed to the auxiliary framework 45 and having an aperture large enough for the spring 48 and shaft 33 to 90 pass therethrough but not large enough for the hub of the disk 50, serves as a stop to limit the movement of the disk 50. The friction disk 50 engages a driving disk 55 secured to a drive shaft 56, the latter having a bearing in each of the posts 46.

For controlling the clutching means there is provided a bellows 70 and a bifurcated arm 71 operated thereby. The bifurcations of the arm 71 engage the groove 51, and 100 movement of the arm thus causes movement of the friction disk 50. The disk 50 is normally held in engagement with the driving disk 55 by the spring 48 acting as a compression spring. The bellows 70 is controlled by 105 means of a suitable electrical valve mechanism 73 which operates to connect the bellows to a suction pipe 74 leading to a suction main 75 and a suitable suction pump of any desired form.

For controlling the operation of a particular action relative to the other actions, there is provided a bellows 80, whose movable member controls a contact arm 81, formed of 5 any suitable material which is a conductor of electricity. The bellows 80 is normally held in open position by a retractile spring 82, and is operated by a pneumatic valve mechanism 83 of well known construction. 10 The valve mechanism 83 is connected by means of a pipe 84 to the control hole 37 in the tracker bar 36, and by a suction pipe 85 to the suction main 75 so that when a hole 39 in the paper strip 35 passes the control hole 37, the bellows 80 will collapse. After 15 the perforation 39 has passed the control hole 37, the valve mechanism 83 disconnects the suction pipe 85 from the bellows 80 and permits restricted entry of air thereto so as 20 slowly to retract the bellows to its normal position, as shown in the drawing, under control of the retractile spring 82.

The several contact arms 81 are connected together by a common conductor 90. Their 25 normally closed contacts are connected by a common conductor 91 to a battery 92. Their normally open contacts are each connected to one terminal of the respective electrical valve mechanism 73, whose other terminal is 30 connected by means of a common conductor 93 to the other pole of the battery 92. Thus the valve mechanism 73 of a particular action is energized by current from the source 92 when the respective bellows 80 is 35 operated provided that at least one of the other bellows 80 is in its normal position. It is understood that the contact arms 81 automatically return to their normal positions as illustrated, whenever the associated bellows 40 is retracted.

The shaft 56 is driven by a common motor 15 the speed of which may be controlled by any usual form of speed control as by a rheostat 99.

45 In the operation of the form of the invention illustrated, the motor 15 is started and its speed regulated so that the shaft 56 will be rotating at the desired speed. The shafts 33 of the player actions 10, 11, 12, 50 13 and 14 will be driven at constant speed by the respective clutching means 16. The drums 31 of all the player actions will then be rotating at the same speed and the paper strips 35 will be wound upon them. Theoretically 55 all the paper strips 35 should move over their respective tracker-bars 36 with the same linear velocity, but due to difference in the stretching of the paper and in the tightness with which it happens to be 60 rolled, this velocity will vary a small amount with each one of the strips 35.

If, for example, the strip 35 of the player action 10 is moving slightly faster than any of the others, the hole 39 in the paper 65 strip 35 will register with the hole 37 in the tracker-

bar 36. This allows air to enter the pipe 84, which operates the valve mechanism 83 so as to deflate the bellows 80 of the control mechanism 21.

The following circuit will then be closed; 70 the battery 92, conductor 93, winding of electrical valve mechanism 73 of the action 10, normally open contact of the contact arm 81, of the control device 21 (now closed because of the operation of the respective bellows), conductor 91 to battery 92; thus operating the valve mechanism of the action 10 and disengaging the driving clutch thereof. The hub of the respective friction disk 50, upon such disengagement, is brought into 75 intimate contact with its bracket 52 and the rotation of the shaft 33 and the roll 31 is stopped. Now as each of the other actions not including the last, comes into position where the respective control holes 37 and 80 39 match, the associated control device and arm 81 are actuated, and the clutching means 85 16 disengaged. Then when the last action catches up to the others, the battery supply 90 through conductor 91 is cut off and all actions are allowed to proceed. They will thus be caused to start synchronously.

It will thus be seen that if any of the actions is in advance of any of the others, all actions in advance will be retarded until 95 the last one has caught up. This operation will take place regardless of which of the actions is in advance, and independent of the number of actions which may be out of step with the others.

The retraction of the bellows 80 is preferably made sufficiently sluggish so that when the last action has caught up with the others the battery circuit will be held open a sufficient time to permit the paper strips 100 to move the control holes 39 out of register with the tracker bar control holes 37.

The inventive thought which this application is based upon is broader than the specific embodiment herein described. The 110 scope of the invention is therefor not to be limited thereby, reference being had to the appended claims for that purpose.

What is claimed is:—

1. An automatic musical instrument comprising player actions for controlling portions of the instrument simultaneously, a common drive therefor, a clutch operatively interposed between the drive and each of the actions, an electromagnet for declutching 115 each of the clutches, and a control device controlled by each of the actions and arranged to actuate the respective clutch provided that at least one other control device is inactive.

2. An automatic musical instrument comprising player actions for controlling portions of the instrument simultaneously, a common drive therefor, a clutch operatively interposed between the drive and each of the 120 130

actions, an electromagnet for declutching each of the clutches, and a control device periodically controlled by each of the actions and arranged to actuate the respective clutch provided that at least one other control device is inactive.

3. An automatic musical instrument comprising player actions for controlling portions of the instrument simultaneously, a common drive therefor, a friction clutch operatively interposed between the drive and each of the actions and normally connecting the drive to the respective action, an electromagnet for declutching each of the clutches, and a control device periodically controlled by each of the actions and arranged to actuate the respective clutch provided that at least one other control device is inactive.

4. An automatic musical instrument comprising player actions for controlling portions of the instrument simultaneously, means for stopping each of said actions including a clutch, a set of contact springs controlled by the respective action, said contact springs including a movable member having a normal position and an off-normal position, the normal contacts of said sets of contact springs being connected together, the movable members of said sets of contact springs being connected together and the off-normal contact of each set of springs being operatively connected to the respective clutch.

5. An automatic musical instrument comprising player actions for controlling portions of the instrument simultaneously, driving means for all of said actions, a normally engaged clutch between each of said actions and said driving means, a pneumatic switch for each of said clutches controlled by the respective actions and a source of energy for operating said clutches arranged to be operatively connected to one of said clutches only when the respective pneumatic switch is actuated and when at least one of the remaining pneumatic switches is inactive.

6. An automatic musical instrument comprising player actions for controlling portions of the instrument simultaneously and actuated by perforated strips respectively, driving mechanism for all of said actions, means operatively interconnecting each of said player actions with said driving mechanism, electrical means for controlling said interconnecting means and a control device for each of said actions periodically con-

trolled by the respective perforated actuating strip and arranged to actuate the respective interconnecting means to disconnect the player action from the driving mechanism provided that at least one other of said control devices is inactive.

7. An automatic musical instrument comprising player actions for controlling portions of the instrument simultaneously and actuated by perforated strips respectively, means for stopping each of said actions including an electromagnetic clutch, a source of electric energy connected to the clutches, and a pneumatic relay connected to be controlled by the perforations in the respective perforated strip, said pneumatic relay including a movable member having a normal position and an off-normal position and including a contact spring normally connected to said movable member and a second contact spring connected to said contact members only when the movable member is in the off-normal position, the normal contacts of all of said pneumatic relays being connected together and to said source of energy, the movable members being connected together, and the off-normal contact of each of said pneumatic relays being operatively connected to the respective clutch.

8. An automatic musical instrument comprising player actions for controlling portions of the instrument simultaneously and actuated by perforated strips respectively, a source of power common to all of said actions, means operatively interconnecting each of said player actions with said power source including an electromagnetic clutch, a pneumatic relay associated with each of said actions and controlled by a row of perforations in the respective perforated strip, each of said pneumatic relays including a movable member, a contact spring normally engaging said movable member, a second contact spring connected to said movable member only when the movable member is off normal, all of said normal contact springs being electrically connected together, all of said movable members being electrically connected together, and means for actuating any of said clutches when the respective pneumatic relay is off normal and at least one of the others of said relays is normal.

In testimony whereof I hereunto affix my signature.

ALBERT D. TRENOR.
